UNITED STATES PATENT OFFICE.

JOHN HAYS HAMMOND, JR., OF GLOUCESTER, MASSACHUSETTS.

ORGAN.

Application filed January 16, 1923, Serial No. 612,953. Renewed June 5, 1928.

This invention relates to pipe organs and more particularly to the control of organs of unlike character operable from a number of manuals.

Some of the objects of this invention are to provide means, in connection with pipe organs, provided with a plurality of manuals, for throwing any one or more of a plurality of organs upon any of the manuals; for reversing or changing this arrangement of organs with respect to the manuals, and for throwing any of the organs which may be on one manual or another on to all manuals. Further objects of this invention are to provide means, in connection with the usual stop action, which will selectively operate any desired series of stops in succession such, for example, as "wood winds", "brasses", etc., and also to provide means in connection with the operation of the swell chests, which are operated from foot pedals, so as to control the swell chests of any organs which may be playing on one of the manuals from a given pedal and to control the swell chests of the organs which are being played from another manual from the other pedal.

In the drawings, Figure 1 shows one portion and Figure 2 another portion of an organ mechanism embodying the features of the invention.

Referring to the illustrated embodiment of the invention shown in the drawings, there is provided a console 10 of conventional design in combination with a musical instrument comprising a plurality of organs such as an organ 11 and an organ 12.

Only so much of the mechanism of the organs is shown as is necessary to an understanding of the invention. The conductors used for control purposes and interconnecting the console and the organs are shown as terminating upon suitable electrical terminals or connectors forming parts of organs of well known construction. The console 10 consists of a plurality of manuals of which two are shown, there being provided an upper manual 15 and a lower manual 16, in combination with a tablet rail 17 having a plurality of tablets for controlling the stops of the various organs, an organ control box 18 for connecting the various organs to one manual or to the other, for reversing the connections or otherwise interchanging them and for connecting the organs together for operation in unison, a pedal mechanism 20 for controlling the swell chests of the organs

and the plurality of selector mechanism such as the selector mechanisms 22 and 23 corresponding in number with the manuals for selectively controlling the various groups of stops. There may be provided such stops of "wood winds", "brasses" or other desired stops. A switching mechanism 25 is provided for interchanging control of the various elements enumerated independently and for connecting the organs together for unison operation independent of the usual controls. A selector mechanism 27 is provided for operatively connecting either of the organs to either of the manuals. A mechanism 29 is provided for operatively connecting the stop action of any of the organs to either selector 22 or 23 and also for operatively connecting the swell chest controlling mechanism to any of the pedals.

The manuals 15 and 16 each include a suitable register of keys such as the keys 31, 32 and 33 pivotally mounted on a substantially horizontal rod 34 in a framework 35 of the console 10. Each key is maintained normally in horizontal position by a suitable retractile spring (not shown) in a well known manner. Each key is provided with a contact plate 37 arranged so that when the respective key is depressed the contact plate engages a pair of conducting springs such as 38 and 39, 40 and 41, 42 and 43. The brushes 38, 40 and 42 of the upper manual 15 are connected to conductors 45, 46 and 47 respectively, and the brushes 39, 41 and 43 are connected together and by way of a common conductor 49 to one terminal of a source of energy such as a battery 50. The brushes 38, 40 and 42 of the lower manual 16 are connected to conductors 52, 53 and 54 respectively and the corresponding brushes 39, 41 and 43 are connected together and to the same pole of the battery 50 by way of a common conductor 55.

The pedal mechanism 20 comprises a suitable plurality of pedals, there being illustrated by way of example two pedals 57 and 58. The pedals are pivotally mounted upon a substantially horizontal rod 59 supported in the framework 35 of the console 10. The interior face of each of these pedals is provided with a circular segment 61 formed of suitable insulating material such as hard rubber or the like and each segment is provided with a strip of conducting material 62. Each of said conducting strips 62 cooperates successively with a plurality of conducting brushes such as 63, 64, 65 and 66. The

brushes 63 are connected together and to the pole of battery 50 above mentioned by way of a common conductor 70 and the conductors 55 and 49. The brushes 64, 65 and 66 of the pedal 57 are connected to conductors 71, 72 and 73 respectively and the brushes 64, 65 and 66 of the pedal 58 are connected to conductors 75, 76 and 77 respectively.

Mounted on the tablet rail 17 is a plurality 10 of tablets such as the tablets, 81, 82, 83, 84, 85 and 86. These tablets are pivotally mounted upon a substantial horizontal rod 87 formed of a material which is a conductor of electricity such as brass or the like, this rod being supported in the framework 35 of the console 10.

The tablets are arranged to be maintained either in the normal position shown or in an off-normal position by means of suitable yielding means (not shown). Upon the reverse strips of each of these tablets there is provided a strip of conducting material 88 connected electrically to the supporting rod 87. A brush 83 formed of flexible spring metal is mounted upon a suitable portion of the frame 35 and insulated therefrom in such manner as to contact with the rod 87. The brush 89 is electrically connected to the pole of the battery 50 mentioned above by way of a conductor 90 and the conductor 49. Mounted 25 upon the frame 35 and insulated therefrom is a plurality of brushes corresponding in number to the number of tablets provided and designated 91, 92, 93, 94, 95 and 96 arranged to contact in the off-normal positions of the 30 tablets with the contact plate 88 of the tablets 81, 82, 83, 84, 85 and 86 respectively. These 35 brushes are connected to conductors 101, 102, 103, 104, 105 and 106 respectively.

The organ control box 18 consists of a plurality 40 of tablets such as the tablets 110, 111 and 112 loosely mounted upon a rod 113, supported in the framework 35. The tablets 110 and 111 are provided on their under surfaces with sheets of conducting material 115 and 116 respectively, which make contact with the rod 113, and which at suitable times cooperate with the brushes 117, 118, 119 and 120. To the tablet 112 is secured a small semi-circular piece of insulating material 125 into which is 45 inserted a segment of conducting material 126, which is electrically connected by a brush 127 to the rod 113. Co-operating with the insulating material 125 and the segment 126 are three brushes 128, 129 and 130 which are 50 secured to the framework 35. The brushes 117 and 118 are connected to conductors 135 and 136 respectively; the brushes 119 and 120 are connected to conductors 137 and 138 respectively and the brushes 128, 129 and 130 are 55 connected to conductors 139, 140 and 141 respectively, the conductor 141 joining the conductor 139. A brush 145 is provided which engages the rod 113, and to which is 60 connected a conductor 146, the other end of 65 which is connected to the conductor 49.

The two group selectors 22 and 23, which consist of two members 150 and 151, made of insulating material and loosely mounted upon rods 152, these rods being supported in the framework 35. To the members 150 and 151 are pivoted links 153 and 154 to the other ends of which are pivoted levers 155 and 156 which are provided with handles 157 and 158. The levers 155 and 156 are loosely mounted upon rods 159 which are supported in the framework 35. The members 150 and 151 are provided with segments of conducting material 164 and 165. Co-operating with the members 150 are four brushes 166, 167, 168 and 169, and co-operating with the members 151 are four brushes 171, 172, 173 and 174. These brushes are supported by parts of the framework 35. The brushes 166, 167, 168 and 169 of the group selector 22 are connected to conductors 180, 181, 182 and 183 respectively, 85 and the brushes 171, 172, 173 and 174 of the group selector 22 are connected to conductors 185, 186, 187 and 188 respectively. The conductors 183 and 188 are connected to the conductor 49. The brushes 166, 167, 168 and 169 of the group selector 23 are connected to conductors 190, 191, 192 and 193, the conductor 193 being connected to the conductor 55; the brushes 171, 172, 173 and 174 of the group selector 23, are connected to conductors 196, 197, 95 198 and 199, the conductor 199 being connected to the conductor 193.

The mechanism 27 which is for throwing any organ on either of the two manuals 15 or 16 consists of a base plate 201 upon which are mounted four rolls 202, 203, 204, and 205, each of which consists of a rotatable member 207 mounted rigidly upon a shaft 208, which is supported by brackets 209 and 210. Rigidly secured to the shafts 208 are armatures 212 105 made of magnetic material, and springs 213 are provided to hold these armatures in the positions shown. Electromagnets 215 are located adjacent to the armatures 212, and when energized, serve to rotate these armatures about the axes of the rods 208. To the members 207, which are made of insulating material, are secured contact strips 217, 218 and 219. Co-operating with the contact strips 217, 218 and 219 of the rolls 202 and 204 are the three conductors 47, 46 and 45 respectively, which are supported by the brackets 221 and 222. Co-operating with the contact strips 217, 218, and 219 of the rolls 203 and 205 are the wires 54, 53 and 52 respectively, which are supported by the brackets 223 and 224. The contact strips 217, 218 and 219 of the rolls 202 and 203 are connected by conductors 230, 231 and 232 to the terminals 233, 234 and 235 of the organ 11. The contact strips 217, 218 and 219 of the rolls 204 and 205 are connected by conductors 240, 241 and 242 to the terminals 243, 244 and 245 of the organ 12. The terminals 233, 234 and 235 of the organ 11 and the terminals 243, 244 and 245 of 110 115 120 125 130 135 140 145 150 155 160 165 170 175 180 185 190 195 200 205 210 215 220 225 230 235 240 245 250 the organ 12 control the playing of the notes which correspond to the keys 33, 32, and 31 of both the manuals 15 and 16.

The mechanism 29 consists of a base plate 250 in which are mounted four rolls 251, 252, 253 and 254. Each roll consists of a rotatable member 255 which is rigidly mounted upon a rod 256 supported in brackets 257 and 258. Rigidly secured to the rods 256 are armatures 260 made of magnetic material, to one end of which are connected the springs 261. Electro-magnets 263 are secured adjacent to the armatures 260, and when energized, serve to rotate these together with the members 255. Rigidly secured to the members 255 are six contact strips 265, 266, 267, 268, 269 and 270. At suitable times the contact strips 265, 266 and 267 of the rolls 251 and 252 make contact with the conductors 77, 76 and 75 which are supported upon brackets 273, 274, and the contact strips 265, 266 and 267 of the rolls 252 and 254 at suitable times make contact with the conductors 73, 72 and 71 which are supported by the brackets 275, 276 and 273. The contact strips 268, 269 and 270 of the roll 251 at suitable times make contact with the conductors 192, 191 and 198 which are supported by the bracket 273. The contact strips 268, 269 and 270 of the roll 252 at suitable times make contact with the conductors 182, 181 and 187 which are supported by the bracket 275. The contact strips 268, 269 and 270 of the roll 253 at suitable times make contact with the conductors 190, 197 and 196, which are supported by the bracket 274. The contact strips 268, 269 and 270 of the roll 254 at suitable times make contact with the conductors 180, 186 and 185 which are supported by the bracket 276. The contact strips 265, 266 and 267 of the rolls 251 and 252 are connected by conductors 280, 281 and 282 to the terminals 283, 284, and 285 which control the swell chests of the organ 11. The contact strips 265, 266 and 267 of the rolls 253 and 254 are connected by conductors 287, 288 and 289 to the terminals 291, 292 and 293 which control the swell chests of the organ 12. The contact strips 268, 269 and 270 of the rolls 251 and 252 are connected by conductors 295, 296 and 297 to the terminals 298, 299 and 300 which control the stop action of the organ 11. The contact strips 268, 269 and 270 of the rolls 253 and 254 are connected by conductors 301, 302 and 303 to the terminals 305, 306, and 307, which control the stop action in the organ 12. The stop actions of the two organs 11 and 12 are connected to the tablets of the tablet rail 17, the conductors 101, 102, 103, 104, 105, and 106 being connected to the conductors 303, 302, 301, 297, 296 and 295 respectively.

The switch mechanism 25 is mounted upon a base plate 311 and consists of two rolls 312 and 313. Each roll consists of a rotatable member 315 mounted rigidly upon a rod 316

which is supported in brackets 317. Rigidly secured to the rods 316 are armatures 318 to one end of which are secured springs 319. Adjacent to the armatures 318 are electro-magnets 321 which when energized cause the armature 318 and the member 315 to be rotated; the springs 319 returning the same to the initial position when the magnets are de-energized. Rigidly secured to each member 315 are four strips 324, 325, 326 and 327, which at suitable times engage conductors 330, 331, 332 and 333. The conductors 330, 331, 332 and 333 are connected to conductors 138, 137, 136 and 135 respectively. One side of the winding of the magnet 321 of the roll 312 is connected to the conductor 140, and one side of the winding of the magnet 321 of the roll 313 is connected to conductor 139; the other sides of these windings are connected by a conductor 335 to the battery 50. The contact strips 324 of the roll 312 and 325 of the roll 313 are connected together by a conductor 340. The contact strips 325 of the roll 312 and 324 of the roll 313 are connected by conductor 341. The contact strips 323 of the roll 312 and 327 of the roll 313 are connected together by a conductor 342, and the contact strips 327 of the roll 312 and 326 of the roll 313 are connected together by a conductor 343.

The winding of the magnet 263 of the roll 251 is connected by a conductor 350, to the winding of the magnet 215 of the roll 203; the winding of the magnet 263 of the roll 252 is connected by a conductor 351 to the winding of the magnet 215 of the roll 202; the winding of the magnet 263 of the roll 253 is connected by conductor 352; to the winding of the magnet 215 of the roll 205 and the winding of the magnet 263 of the roll 254 is connected by a conductor 353 to the winding of the magnet 215 of the roll 204.

The conductor 350 is connected by a branch conductor 355 to the conductor 341; the conductor 351 is connected by a branch conductor 356 to the conductor 340; the conductor 352 is connected by a branch conductor 357 to the conductor 343 and the conductor 353 is connected by a branch conductor 358 to the conductor 342. The other sides of the windings of the solenoids of the four magnets 263 and the four magnets 215 are connected by common return wires 361 to the wire 335; and thus to one side of the battery 50. A conductor 365 is provided from the organ 11 to the conductor 361 and the conductor 366 is provided from the organ 12 to the conductors 361. These conductors carry the return current from all the circuits in the respective organs.

In operation the tablets of the organ control box 18 control the rolls on the switching mechanisms 27 and 29. If, for example, the tablet 112 is in the position shown a circuit will be formed through the brush 129, con-

ductor 140, magnet 321 of the roll 312, conductor 335, battery 50, conductor 146, brush 145, rod 113, brush 127 and segment 126. This energizes the magnet 321 of the roll 312 which is thereby rotated bringing the contact strips 324, 325, 326, and 327 in contact with the conductors 330, 331, 332 and 333. If it should now be desired to throw organ 11 upon the upper manual 15 the tablet 111 is rotated about the bar 113 so as to depress the upper end thus bringing the contact 120 into engagement with the plate 116 which closes the circuit through conductors 138, 330, contact strip 324, conductors 340, 356, 351, 15 through the winding of the magnet 215 of the roll 202, the conductors 361, 335, battery 50, conductor 146, brush 145, rod 113 to the plate 116. This energizes the magnet 215 of the roll 202 which causes it to rotate the member 207 thus bringing the contact strips 217 and 218 and 219 in engagement with the conductors 47, 46 and 45 respectively.

In this way the three brushes 38, 40 and 42 of the upper manual 15 are connected to the terminals 235, 234 and 233 of the organ 11 so that when any one of the three keys 31, 32 or 33 is depressed it will close the circuit through the corresponding primary magnet (not shown) in the organ 11 which will cause the corresponding note of that organ to be actuated.

If it is desired to play the organ 11 from the lower manual 16 the tablet 111 is rotated so as to depress the lower end thus closing a similar circuit through the magnet 215 of the roll 203 which causes the member 207 to be rotated so as to bring the contact strips 217, 218 and 219 into engagement with the conductors 54, 53 and 52 respectively. The lower manual 16 will then be connected to the organ 11 and by depressing any of the keys of this manual it will cause the corresponding notes in organ 11 to be actuated. The organ 12 is controlled in a similar manner by the tablet 110 so that when the upper end of this tablet is depressed it will connect the organ 12 to the upper manual 15 and when the lower end of the tablet 110 is depressed it will connect the organ 12 with the lower manual 16.

The operation of the reversing mechanism is as follows: If, for example, organ 11 is being controlled on the upper manual 15 and organ 12 is on the lower manual 16 and it is desired to reverse this arrangement without touching the tablets 111 and 110 the tablet 112 is depressed at its lower end thus connecting the segment 126 with the brush 128. This causes the magnet 321 of the roll 313 to be energized thus connecting the contact strips 324, 325, 326 and 327 with the conductors 330, 331, 332 and 333 and at the same time de-energizing the magnet 321 of the roll 312 thus allowing the member 315 of the roll 312 to be rotated into its initial position under the ac-

tion of the spring 319. This reverses the connections of the conductors 356, 355, 358 and 357 so that instead of energizing the magnet 215 of the roll 202 the magnet 215 of the roll 203 is energized and instead of energizing the magnet 215 of the roll 205 the magnet 215 of the roll 204 is energized. This causes the organ 11 to be thrown on the lower manual 16 and the organ 12 on the upper manual 15. In this way any organ that may be on one of the manuals is shifted to the other and vice-versa.

If it is desired to throw any organ which may be on either one of the two manuals on to both of the manuals the tablet 112 is depressed at the upper end thus connecting segment 126 to the brushes 129 and 130. This energizes both the magnets 321 of the rolls 312 and 313 so that the magnets 215 of the rolls 202 and 203 are thrown in parallel and the magnets 215 of the rolls 204 and 205 are thrown in parallel. If the tablet 111 is depressed at either end it will therefore cause the organ 11 to be thrown on both manuals 15 and 16 and if the tablet 110 is depressed at either end it will cause the organ 12 to be thrown on both manuals 15 and 16, thus producing the unison effect.

The tablets of the tablet rail 17 control the stop action of the two organs 11 and 12, that is, the tablets 81, 82 and 83 control the stop action operated from the terminals 307, 306 and 305 of the organ 12 by means of the brushes 91, 92 and 93 and the conductors 101, 102 and 103 and the tablets 84, 85 and 86 control the stop action of the organ 11, which are connected to the terminals 300, 299 and 298, by means of the brushes 94, 95 and 96 and conductors 104, 105 and 106.

The rolls 251, 252, 253 and 254 of the switching mechanism 29 are operated at the same time as the rolls 203, 202, 205 and 204 respectively, as the magnets 263 are connected in parallel to the respective magnets 215. For example, if the tablet 111 is depressed at its lower end so as to throw the organ 11 upon the lower manual 16 by energizing the magnet 215 of the roll 203, the magnet 263 of the roll 251 will be energized thus rotating the member 255 which will bring the contact strips 265, 266, 267, 268, 269 and 270 in contact with the conductors 77, 76, 75, 192, 191 and 198 respectively. This connects the three terminals 283, 284 and 285 which control the swell chest of the organ 11 by means of the conductors 280, 281 and 282, contact strips 265, 266 and 267 of the roll 251, conductors 77, 76 and 75 to the brushes 66, 65, and 64 of the pedal 58. When the pedal 58 is rotated about the bar 59, contact segment 62 successively engages the brushes 64, 65 and 66 successively closing the circuits through the terminals 285, 284 and 283, the return current passing through the conductors 365, 361, battery 50, conductors 49, 130

55 and 70, brush 63 to the contact strip 62 which is always in engagement with this brush. Therefore, as the pedal 58 is gradually rotated the circuits controlling the swell 5 chest in the organ 11 will be successively energized to operate the shutters of the swell chest in a well known manner. If the tablet 111 is depressed at its upper end so as to throw the organ 11 on the upper manual 15, the member 255 of the roll 252 will be rotated under the action of the magnet 263 and will thus connect the terminals 283, 284 and 285 by means of the conductors 280, 281, 182, 73, 72 and 71 to the brushes 66, 65 and 64 of the pedal 57 which will then control the action of the swell chest instead of the pedal 58.

The tablet 110 controls the member 255 of the rolls 253, and 254 in a similar manner to that just described so that when the organ 12 20 is thrown on the lower manual 16 the swell chest of this organ which is controlled from the terminals 291, 292 and 293 will be operated by the pedal 58, and when the organ 12 is thrown on the upper manual 15 the swell 25 chest will be operated by the pedal 57. It will be seen from this that the swell chests of all of the organs which are on the upper manual 15 will be controlled by the pedal 57 and the swell chests of all the organs which 30 are on the lower manual 16 will be controlled from the pedal 58.

When the organ 11 is thrown on the upper manual 15 and the member 255 of the roll 252 is operated the terminals of the stop action 298, 299 and 300 of the organ 11 will be connected by conductors 295, 296 and 297, contact strips 268, 269 and 270 of the roll 252, conductors 182, 181 and 187 to the brushes 168, 167 and 173 of the selector mechanism 22. When the organ 12 is thrown on the upper manual 15 the member 255 of the roll 254 is operated so as to connect the terminals 305, 306 and 307 of the stop action of the organ 12 by conductors 301, 302 and 303, contact strips 268, 269 and 270 of the roll 254, conductors 180, 186 and 185 to the brushes 166, 172 and 171 of the selector mechanism 22.

It will therefore be seen that the stop action of each organ that is operated from the upper manual will be brought down to the selector mechanism 22 and distributed through to the two sets of brushes which correspond to the "wood winds" and the "brasses" respectively, the stops operated by the terminals 305, 298 and 299 being "wood winds" and the stops operated by the terminals 307, 306 and 300 being "brasses". When the lever 155 is rotated manually it rotates the member 150 in a counter clockwise direction. This brings the segment 164 into successive engagement with the brushes 168, 167 and 166 thus successively closing the circuit through the terminals 298, 299 and 305 65 which successively operates the "wood wind"

stops of the organs which are being played on the upper manual 15. When the lever 156 is rotated manually the segment 165 is brought into successive engagement with the brushes 173, 172 and 171 which energizes the 70 circuits through the terminals 300, 306 and 307 thus successively operating the "brasses" of the organs which are being played on the upper manual 15.

When the organs 11 and 12 are played 75 upon the lower manual 16 the rolls 251 and 253 are operated and connect the stop action of the two organs to the brushes of the selector mechanism 23 in a similar manner to that just described.

The "wood winds" of these two organs are then successively brought into action by manually moving the lever 155 and the "brasses" of these two organs are successively operated by manually moving the lever 156. It is 80 seen from this description that all the "wood winds" and the "brasses" of any of the organs which are being played on the upper manual 15 are successively brought into action by the selector mechanism 22 and all the "wood 85 winds" and the "brasses" of any of the organs which are being played on the lower manual 16 are successively brought into action by the selector mechanism 23.

The invention upon which this application 90 is based is broader than the specific embodiments shown and described for the purposes of illustrating some of the ways in which it may be employed. The scope of the invention is therefore understood not to be limited by the present specific description. I 95 intend no limitations other than those imposed by the appended claims.

I claim:

1. An organ having two departments, each 100 with a plurality of note actions tuned to the notes of the musical scale, a pair of manuals each having keys corresponding to notes of the musical scale, selecting means including tablets and relays controlled by the tablets for operatively interconnecting the keys of one manual with the note actions of a predetermined department respectively, and means for modifying at will the connections between said tablets and said relays.

2. An organ having two departments, each 110 with a plurality of note actions tuned to the notes of the musical scale, a pair of manuals each having keys corresponding to notes of the musical scale, selecting means including tablets and relays controlled by the tablets for operatively interconnecting the keys of one manual with the note actions of a predetermined department respectively, and means for reversing at will the connections between 115 said tablets and said relays.

3. In a musical instrument, a plurality of 120 manuals, a plurality of organ chests, a selecting device including electro-magnetic relays, the number of electro-magnetic relays being 125

the product of the number of manuals times the number of organs, contact making devices for controlling said relays, and means for modifying the connections between the contact making devices and the relays.

4. In a musical instrument, a pair of manuals, a pair of organ chests, a selecting device including electro-magnetic relays, the number of electro-magnetic relays being the product of the number of manuals times the number of organ chests, contact making devices for controlling said relays, and means for reversing the connections between the contact making devices and the relays.

15 5. In a musical instrument, the combination with a pair of organs each having a plurality of note actions, stop actions and swell chests, a pair of manuals each having a plurality of keys, a pair of selecting mechanisms,

and a pair of pedals, of a selecting device 20 including relays for connecting the note actions of either of said organs to the keys of either of said manuals respectively, a selecting device including relays for connecting the stop action of either of said organs and 25 for connecting the swell chest of either of said organs to either pedal, a contact closing device, an electro-magnetic mechanism for establishing connections from said contact closing device to said relays in one order, 30 and a second electro-magnetic mechanism for establishing connections from said contact closing device to said relays in a different order.

In testimony whereof I hereunto affix my 35 signature.

JOHN HAYS HAMMOND, JR.
